UNITED STATES PATENT OFFICE.

PATRICK J. CONLEY, OF GALVESTON, TEXAS.

LOCOMOTIVE FIRE BOX.

Application filed October 19, 1925. Serial No. 63,377.

This invention relates to new and useful improvements in a locomotive fire box.

One object of the invention is to provide a boiler having an improved type of fire box and adapted for general use, and more particularly for application to locomotives whereby a more efficient utilization of the fuel will be accomplished.

Another object of the invention resides in 10 a novel construction whereby the initial air entering the fire box, or furnace, will be pre-heated.

A further feature of the invention resides in the provision of means whereby a portion 15 of the hot vapors from the firebox containing unconsumed carbon, may be returned to the firebox, or furnace resulting in the complete combustion of said carbon and a more efficient combustion of the fuel delivered into 20 the furnace from the burner.

A still further feature of the invention resides in the provision of a novel type of boiler furnace equipped with means for controlling the supply of air thereto to the end that said 25 furnace may be completely closed when the fire is extinguished to retain the heat in the furnace and to prevent sudden changes of temperature and the consequent injury to the furnace caused thereby.

With the above and other objects in view 30 this invention has particular relation to certain novel features of construction, operation and arrangement of parts, an example of which is given in this specification and illustrated in the accompanying drawings, wherein:—

Figure 1 shows a longitudinal sectional view of the improved type of boiler, equipped with a novel type of oil burning furnace, and

Figure 2 shows a cross sectional view thereof, taken on the line 2—2 of Figure 1.

Referring now more particularly to the drawings, wherein like numerals of reference designate similar parts in each of the figures, 45 the numeral 1 designates the boiler as a whole which is provided with the furnace 2. In the type shown in Figures 1 and 2 the furnace is supplied with fuel from the burner 3, which is anchored to the front wall thereof, and 50 which is enclosed in the chamber 4, adjacent the front side of the furnace. This chamber has an air inlet 5, which is controlled by the valve, or shutter 6.

Above the chamber 4 there is a transverse flue 7, whose top and side walls lie adjacent 55 the furnace forming a part of the bottom of

said furnace. These walls are hot and heat the air passing through said flue before it enters the furnace. The air for the furnace enters the inlet 5 and passes thence upwardly 60 into the flue 7, at one end, and thence along said flue to its other end, and thence downwardly through the passageway 8 into the main air flue 9 which enters the furnace 2 65 from beneath.

The boiler has the usual smoke stack 10 near its front end in front of the boiler tubes 11. There is a vapor line 12, one end of which projects into the front end of the boiler, and terminates in the smoke box adjacent the 70 smokestack, and whose other end enters the main air flue 9. The furnace draft will create a suction through the line 12 but a nozzle pipe 12' may be connected with a convenient steam line of the boiler and its discharge end 75 turned into the upper end of the vapor line so that a forced draft may be thereby created through said line 12, if desired.

A part of the products of combustion will 80 pass out of the smoke stack, but a considerable portion thereof will be diverted through the vapor line 12, and returned to the furnace for further consumption. These hot vapors will also mingle with the fuel being ejected from the burner resulting in a more complete 85 combustion thereof.

The oil line 13, which supplies oil to the burner 3 has a control valve 14, which is controlled by the valve rod 15. This rod has a lateral arm 16 and the stem of the valve, or 90 shutter, 6 has an arm 17, fixed thereto, and the arms 16 and 17 are connected by a link 18 to the end that the shutter 6 will be opened and closed simultaneously with the corresponding movements of the valve 14, and the 95 air supply controlled to meet the requirements of the fuel supply. When the fuel is completely cut off and the fire extinguished the air inlet will also be completely closed to prevent the inlet of cold drafts of air and a 100 too sudden cooling of the interior of the furnace.

What I claim is:—

1. In a boiler having a furnace and having a chamber adjacent the front end of the 105 furnace and a main air flue entering the furnace beneath the chamber, said chamber being provided with an air inlet, a valve controlling said inlet, a transverse air flue above said chamber whose top and side walls lie adjacent the furnace, said inlet entering said transverse flue at one end and there being a 110

passageway leading downwardly into the main air flue from the other end of said transverse flue, a vapor line leading from the front end of the boiler and terminating in the main air flue of the furnace.

2. In a boiler having a furnace at one end and a smoke box at its other end and tubes between said furnace and smoke box, a main air flue entering the forward end of the furnace, a chamber above said main air flue having an air inlet, a shutter valve controlling

said inlet, a transverse flue above said chamber one end of which communicates with the chamber there being a passageway connecting the other end of the transverse flue with 15 said main air inlet and a vapor line leading from the smoke box of the boiler in front of said tubes and entering the main air inlet.

In testimony whereof I have signed my name to this specification.

PATRICK J. CONLEY.
